UNITED STATES PATENT OFFICE.

JAMES C. GRANT, OF STAMFORD, CONNECTICUT.

LABELING DEVICE FOR LOOSE-LEAF BINDERS.

1,403,076.

Specification of Letters Patent. Patented Jan. 10, 1922.

Application filed May 10, 1920. Serial No. 380,117.

To all whom it may concern:

Be it known that I, JAMES C. GRANT, a citizen of the United States, and a resident of Stamford, in the county of Fairfield and State of Connecticut, have invented new and useful Improvements in Labeling Devices for Loose-Leaf Binders, of which the following is a specification.

This invention relates in general to a labeling device for record files and the like, and more particularly to a device of this character especially adapted for use upon the conventional open back loose-leaf record books.

Heretofore, identification data for indicating the contents of open back loose-leaf books which comprise a pair of covers connected together at one end thereof with clamping devices with the leaves of the book removably held between the said covers by the said clamping devices, has by necessity been applied to the books by sticking a label or the like to the outside of one of the covers of the book. When a number of books so labeled are piled together in a case or on a shelf it is usually necessary in order to find the book containing certain data to go through the pile one book at a time until the desired one was found, such procedure obviously reducing the efficiency of the office handling the books.

The objects of my invention are to provide a device whereby the identification data can be applied to the clamped end of a loose-leaf book of the character above described so that when a number of such books are piled on a shelf or the like with the clamped ends outward, the identification data of all the books are visible at a glance and any desired book can be easily located without disturbance of the other books; to provide a holder for a card or label bearing the identification data which can be easily and quickly applied to the clamped end of any loose-leaf book of the character described; to provide such a holder which will be positively but detachably held in position by the clamping means holding the leaves between the covers of the book; to provide such a device constructed to slip between the leaves of a loose-leaf book and be held in position thereby; to so construct a device of this character that a portion thereof will pierce the ad-

jacent leaves of the book when the same are clamped together to prevent the device from slipping from the book; to provide such a card holder which can be easily removed from a book without injury to leaves thereof; to provide a card holder of the character described adapted to interchangeably receive identification cards or labels; to construct the card holder to prevent injury thereby to a desk or the like upon which a book carrying the holder may be laid, and to obtain other objects and results as may be brought out by the following description.

Referring to the accompanying drawings, in which like numerals of reference indicate the same parts throughout the several views,

Figure 1 is a perspective view of a labeling device embodying my invention, showing the same as applied to a conventional type of loose-leaf book;

Figure 2 is a horizontal sectional view through the clamped end of the book, the labeling device being shown in edge elevation;

Figure 3 is a front elevation of the labeling device detached from the book;

Figure 4 is a transverse vertical sectional view of the same taken on the line 4—4 of Fig. 3;

Figure 5 is a horizontal sectional view taken on the line 5—5 of Fig. 3;

Figure 6 is a front elevation of a modified form of the labeling device, and

Figure 7 is a vertical sectional view taken on the line 7—7 of Fig. 6.

In Figure 1 of the drawings I have shown one conventional type of loose-leaf binder with which my invention is adapted to be used, the said binder comprising a pair of covers 1 and 2 which are constructed of some suitable stiffening material such as the cardboard 3 covered by any suitable material such as leather or fabric casing 4. Each of the covers comprises a clamping or binding portion 5 to which is hingedly connected by the flexed portion 6 of the casing 4 the swinging portion of the covers 1 and 2. The binding portion 5 of one of the covers, in the present instance the cover 1, is provided with outwardly projecting clamping pins 7 which are adapted to pass through openings 8 in the binding section 5 of the cover 2, a clamping screw 9, see Figure 2, being mounted in

the cover 2 for engaging one of the pins 7 to hold the covers in a fixed relation to each other. Any desired number of leaves or pages 10 are adapted to be clamped between the said covers 1 and 2, the said leaves being formed with notches 11 in one end thereof to loosely fit over the respective pins 7. In clamping the leaves between the covers, the cover 2 is removed and the desired number of pages slipped over the clamping pins 7, after which the cover 2 is slipped over the pins 7 and pressure exerted thereon to tightly bind the leaves 10, after which the clamping screw 9 is tightened against its corresponding pin 7 to hold the leaves and covers in clamped position. The above-described construction is all conventional and no claim to novelty is made thereon.

The form of my invention illustrated in Figures 1-5 inclusive comprises a rectangular strip of suitable metal, such as brass, the ends of which are bent at substantially right angles to form a central card holding body portion 12 and opposed flanges 13 which are adapted to slip between the leaves 10 of the loose-leaf book. These flanges 13 are formed with suitable means for positively engaging the adjacent leaves 10 of the book, in the present instance the said means comprising a plurality of pointed projections 14 which may be conventionally formed by punching rectangular holes outwardly from the flanges 13. The card holding portion 12 is formed with a plurality of upstanding flanges 15 which may be conveniently stamped from the body portion of the metal and project outwardly from the card holding portion 12 of the labeling device, portions of said flanges being arranged substantially parallel to the body portion of the device. In the present instance three of these flanges 15 are shown as arranged along three sides of the card holding portion 12, and a suitable card 16 bearing any desired inscription or identification matter is slipped under said flanges from the fourth side of the card holding portion 12, the said card being held in position between the said flanges and the body portion of the device. A flange 17 projecting substantially at right angles from the card holding portion 12 is disposed upon the fourth side of the card holding portion adjacent the free edge of the card, so as to prevent the card from slipping from under the flanges 15. The body portion of the device may be formed with a suitable opening 18 through which a finger of the user may be inserted against the rear of the card for the purpose of pushing the same outwardly beyond the edge of the flange 17 to remove the card from beneath the flanges 15. It is desirable to provide means for pre-

venting the flanges 15 and 17 from scratching a desk or the like upon which the book carrying the labeling device may be set and for this purpose the card holding portion 12 may be provided adjacent the edges thereof with an outwardly projecting rib 19 which may be conveniently pressed outwardly from the body portion of the device so that when the book carrying the labeling device is set upon its clamped edge 75 the rib 19 will engage the support and space the flanges 15 and 17 therefrom.

In applying the device to a loose-leaf book as shown in Figure 1, the cover 2 is loosened and the pages of leaves 10 of the book 80 slightly separated, after which the flanges 13 of the labeling device are slipped between the leaves of the book as shown in Figure 2. Pressure is then exerted upon the cover 2 in order to tightly bind the leaves 10, the said pressure causing the pointed projections 14 to pierce adjacent leaves so as to prevent the device from slipping from between the leaves, and when the clamping screw 9 is tightened the labeling device is securely held 90 in position between the leaves of the book. In removing the labeling device from the book it is merely necessary to loosen the cover 2 and raise the upper leaves 10 from the pointed projections 14 of one of flanges 13 95 and then raise the other flange from its adjacent leaves, after which the device can be easily slipped outwardly from between the leaves, the smooth inner sides of the flanges 13 easily slipping from the leaves 10 between 100 the said flanges. Injury to any of the leaves 10 of the book as by tearing or scratching, is prevented.

In the modified form of the invention illustrated in Figures 6 and 7, the device is 105 formed of a rectangular strip of material in substantially the same manner as above described, the said device comprising the flanges 20 adapted to slip between the leaves of the book, and the card holding portion 21 110 of the device comprising a frame which is formed by cutting out the center of the card holding portion as indicated at 22, the frame or margin of the card holding portion being in the form of an outwardly bulged rib 23. 115 Card holding prongs 24 may be conveniently struck up from the flanges 20 adjacent the frame of the card holding portion, and one of the free edges of the frame may be provided with a similar card holding prong 25, the card being slipped between the said prongs 24 and 25 in a manner similar to that in which the card 16 is secured between the flanges 15 and the card holding portion 12 of the construction above described. The 125 side of the frame opposite the prong 25 may be formed with a lug 26 to hold the card between the flanges 24 and 25 substantially as does the flange 17 of the construction shown by Figures 3 and 4.

While I have shown the device used in connection with one conventional type of binder, it will be obvious that the device is equally well adapted for use with many other types of binders, and it will be seen that my invention eliminates the trouble and inconvenience heretofore caused by the attachment of identification data to such binders to the outside of one of the covers where binders so marked are piled one upon another. Other card holding means than the flanges above described, and other means than the pointed projections 14 for securing the device between the leaves of a book may be provided, and various other modifications and changes may be made in the construction of the invention without departing from the spirit or scope thereof. Therefore I do not desire to be limited in the construction of my invention except as required by the following claims when construed in the light of the prior art.

Having thus described the invention, what I claim is:

1. The combination with a loose-leaf book having a pair of covers and means for clamping a plurality of loose-leaves between the said covers, of a labeling device provided with a pair of spaced flanges, said flanges adapted to be secured between the said leaves of the book and held in position by the said clamping means for the leaves of the book.

2. The combination with a loose-leaf book having a pair of covers and means for clamping a plurality of loose-leaves between the said covers, of a labeling device having angular portions projecting therefrom, said angular portions adapted to be slipped between the leaves of a loose-leaf book and provided with means to positively engage the adjacent leaves of the book to hold the device in position.

3. The combination with a loose-leaf book having a pair of covers and means for clamping a plurality of loose-leaves between the said covers, of a labeling device having spaced flanges projecting from the rear thereof, said spaced flanges adapted to be slipped between the leaves of a loose-leaf book and embrace a plurality of said leaves therebetween, said flanges being provided with means to pierce adjacent leaves of the book to hold the device in position.

4. A labeling device comprising a body portion having rearwardly extending flanges adapted to slip between the leaves of a loose-leaf binder, said flanges being provided with means projecting beyond the surface thereof to positively engage the adjacent leaves.

5. A labeling device comprising a body portion having a pair of spaced flanges arranged at an angle to said body portion, said flanges being adapted to slip between the leaves of a loose-leaf book and embrace a plurality of said leaves between them, said

flanges being provided at their outer sides with means to positively engage adjacent ones of said leaves.

6. The combination with a loose-leaf binder comprising a pair of covers and means for clamping a plurality of leaves between said covers, of a labeling device to indicate the contents of the binder to which it is attached, said device comprising a body portion having a plurality of rearwardly extending flanged portions adapted to slip between the said leaves said flanges being held in position between said leaves by the said leaf clamping means.

7. A labeling device comprising a body portion having a pair of spaced flanges arranged at an angle to said body portion, said flanges being adapted to slip between the leaves of a loose-leaf book and embrace a plurality of said leaves between them, said flanges being provided at their outer sides with outwardly extending projections to pierce adjacent ones of said leaves to maintain the device in position.

8. A labeling device comprising a body portion having a pair of flanges arranged at substantially right angles thereto, the adjacent sides of said flanges being smooth and flat while the outer sides thereof are formed with projections.

9. The combination with a loose-leaf binder comprising a pair of covers and means for clamping a plurality of leaves between said covers, of a labeling device comprising a body portion having a pair of substantially parallel flanges projecting at substantially right angles thereto, the said flanges being adapted to slip between the said leaves, the adjacent sides of said flanges being flat and smooth while the outer sides thereof are formed with projections, the said projections piercing adjacent leaves when the leaves are clamped together.

10. A labeling device comprising a body portion adapted to lie at the edges of the leaves at the open back of a loose-leaf ledger and having holding means adapted to slip between the said leaves, label receiving means on said body portion, and a rib at the margin of said body portion projecting therefrom to guard the said label receiving means against contact with the surface of a desk or the like.

11. A labeling device comprising a body portion adapted to lie at the edges of the leaves at the open back of a loose-leaf ledger and having a flange adapted to slip between the said leaves, label receiving means on said body portion, and a rib at the margin of said body portion projecting therefrom beyond the said label receiving means.

12. A labeling device comprising a body portion adapted to lie at the edges of the leaves at the open back of a loose-leaf ledger and having flanges adapted to enter between

the leaves and be clamped there, label receiving means on said body portion, and a rib around the margin of said body portion projecting therefrom beyond the said label receiving means.

13. A labeling device comprising a card holding body portion having angular ex-

tensions projecting from opposite ends thereof, said extensions adapted to be secured between the leaves at the open back of a loose-leaf book to maintain the device in position. 10

JAMES C. GRANT.
